UNITED STATES PATENT OFFICE

PAUL ZENKER, OF PARIS, FRANCE, ASSIGNOR TO HAVILAND & CO. (SOCIETE ANONYME),
OF LIMOGES, FRANCE, A CORPORATION OF FRANCE

DESIGN FOR A PLATE OR SIMILAR ARTICLE

Application filed May 13, 1930. Serial No. 35,632. Term of patent 3½ years.

To all whom it may concern:

Be it known that I, PAUL ZENKER, a citizen of Finland, residing at Paris, France, have invented a new, original, and ornamental Design for a Plate or Similar Article, of which the following is a specification, reference being had to the accompanying drawing, forming part thereof, in which—

Fig. 1 is a plan view; and

Fig. 2 is a side elevation of a plate showing my new design.

I claim:

The ornamental design for a plate or similar article, as shown.

P. ZENKER.
